UNITED STATES PATENT OFFICE.

GWYNNE L. MARVIN, OF MORGAN HILL, CALIFORNIA.

BED SHIELD.

Application filed October 13, 1922. Serial No. 594,302.

To all whom it may concern:

Be it known that J. GWYNNE L. MARVIN, a citizen of the United States, residing at Morgan Hill, in the county of Santa Clara and State of California, have invented new and useful Improvements in Bed Shields, of which the following is a specification.

This invention relates to improvements in bed shields, the principal object of which is 10 to provide a shield which extends between two persons occupying the same bed for the purpose of protecting these persons against the breath of each other.

Another object is to provide a shield of 15 this character which will act in a sanitary capacity.

A further object is to provide a shield which will contact the bed clothes thereby preventing one person from pulling the 20 clothes from the other person.

Still further objects are to provide a shield which will act as a support for a reading light, and one which may also be employed as a back rest, if desired.

25 Other objects and advantages will be apparent during the course of the following description.

In the accompanying drawings forming a part of this specification, and in which 30 like numerals are employed to designate like parts throughout the same,

Figure 1 is a side elevation of a bed having my shield applied thereto,

Figure 2 is a fragmentary top plan view 35 of Figure 1,

Figure 3 is a detail perspective view of the manner of attaching the shield to a stand, and

40 Figure 4 is a detail perspective view of the stand clamp.

When two persons occupy the same bed, it is often desirous of turning toward the other party occupying the bed, but owing to sanitary conditions, it is often not advisable owing to the fact that one of the parties may be suffering from an infection, such as a cold, which is transferable, and it is often desirable to provide against the removal of the bed clothes from one side of 45 the bed to the other, which results in the uncovering of one of the parties, and at the same time often provides quite a space about the back and shoulders.

50 I propose to overcome these difficulties by

providing a shield made of wood or similar 55 substance which will overlie the upper portion of the bed clothes at a point between the occupants.

In the accompanying drawings wherein for the purpose of illustration is shown a 60 preferred embodiment of my invention, the numerals 6 and 7 refer to the head and foot sections of the bed, respectively. These sections are joined by the usual side rails designated by the numeral 8, upon which a 65 spring 9 is mounted. Upon this spring, the usual mattress 11 is placed, thus making the ordinary bed upon which the bed clothes are spread. In order to clearly illustrate my invention, I have omitted the bed clothes 70 from the present drawing.

The numeral 12 designates a tubular stand which is provided with legs 13 and 14, and it will be noted that the leg 13 is considerably longer than the leg 14, the reason for 75 this being that the leg 14 abuts the base board and consequently must extend beyond the back line of the bed.

Adjustably secured upon the tubular stand 12, I provide a collar 16 which is held in 80 adjusted position by the set screw 17. This collar carries a U shaped member 18 which is adapted to encircle the cross rod 19 of the bed, thus securing the stand to the bed. A sliding rod 21 is adapted to be moved in the 85 tubular support 12 and carries upon its upper extremity a pivoted rod 22 provided with a light 23. Electrical current is carried to this light through the medium of a cord 24 passing through the stand 12 and rods 21 and 22. Slidably secured to the support 12 is a clamp 26, which is split so as to allow for a clamping action accomplished through the medium of a wing nut 27. This clamp 26 carries a flat shield 28 which 90 is adapted to overlie the upper portion of the mattress 11, and it is between this shield and mattress that the bed clothes are spread. A chain 29 is secured to the clamp 26 and extends downwardly and is attached to a 95 spring 31 coiled about the support 12 at a point just above the collar 16.

The operation of my device is as follows:—

Assuming that the parts are in the position shown in Figure 1, and that the bed clothes have been spread upon the mattress 11, the shield will then be pulled down-

wardly by the spring 29 against the bed clothes. If desired the nut 27 can be tightened so as to hold the shield in adjusted position. This will result in the lower edge 5 of the shield contacting the bed clothes and functioning as before mentioned. The light 23 may be adjusted in any convenient manner. During the day time, the shield 10 28 and the light 23 are moved to the dotted line position shown in Figure 2 so as to be inconspicuous, but at the same time quickly available for use, when desired.

It is to be understood that the form of 15 my invention herewith shown and described is to be taken as a preferred example of the same, and that various changes in the shape, size and arrangement of parts may be resorted to without departing from the spirit of the invention or the scope of the sub- 20 joined claims.

Having thus described my invention, I claim:—

1. In a device of the character described, the combination with a bed, a stand adapted to be secured to said bed, a shield movably supported upon said stand, and spring means for maintaining said shield in contact with the covers of said bed. 25

2. In a device of the character described, the combination with a bed, a support comprising a tubular member, a clamp for securing said support to said bed, a clamp vertically movable on said support, a shield secured to said clamp, and spring means for holding said shield in contact with the cov- 30 ers of said bed. 35

In testimony whereof I affix my signature.

GWYNNE L. MARVIN.
